6 Claims. (Cl. 156—155)

The invention disclosed herein is concerned with a method of and a device for providing thin emission coatings or layers upon carriers for directly or indirectly heated cathodes of electrical discharge vessels, comprising placing upon the smooth surface of a pliable supporting film a layer of an emission paste intermixed with binder and softener agents, and thereupon bonding such supporting film with its emission layer to a cathode carrier, and with a cathode body prepared thereby for operation thereof in a discharge vessel.

It is in addition to orthodox methods of producing emission layers, which have considerable drawbacks, especially in the processing with automatically operating machinery, known to produce emission layers by making a paste layer which is bonded to a cathode carrier. For example, it is known to produce a paste layer by spraying or pouring a paste upon the smooth surface of a support, for example, a glass support, whereupon such layer is after drying thereof peeled from the support and bonded to a cathode carrier such as a tantalum wire spiral. However, it is in practicing such method, owing to the rigidity of the relatively thick glass support very difficult to peel or to lift therefrom a compact paste layer and to place such layer upon the carrier surface, without damaging the layer, even when a considerable amount of binder material had been added to the paste.

Another known method avoids part of these drawbacks by putting the paste film upon a pliable support from which the layer can be more readily removed.

The bonding of the paste to a cathode carrier requires in the known method that it be removed from the support prior to the bonding or incident thereto, and it is therefore necessary that the paste layer has a particularly good cohesion, which is obtained by the use of increased amounts of customary binding agents. However, it is known that serious difficulties appear in the operation of cathodes having emission layers containing an appreciable amount of binder material.

The object of the invention is to propose a method of producing very uniform and dense emission layers with smooth surfaces, which are adapted for mass production, and in which the above described drawbacks are to a large extent avoided.

This object is in accordance with the invention realized by placing upon a very thin supporting film a paste layer consisting substantially of alkaline earth carbonate and thereupon bonding such supporting film with its paste layer to a cathode carrier or cathode shell.

The support used for this purpose is a film of synthetic material of a composition, such that it decomposes in the discharge vessel incident to the decomposing of the paste layer taking place in the cathode activation, without leaving any disturbing residue or liberating aggressive gases. A solution of dinitrocellulose, such for example, as a solution of collodion cotton, which is commercially available under the designation E1440, is advantageously employed for making the film operating as a support for the emission layer. The solvent for the initial solution for making the film must be selected with consideration of the fact

that the emission layer is placed thereon throughout in the form of an emulsion, namely, an emission paste which contains an approximately identical or a similar binder, thus containing corresponding solvents, so that the produced film support is in no way completely dissolved again incident to receiving the emission layer, by the solvent contained in the latter, but is merely partially partially slightly softened, thereby securing a good adhesion of the paste of the emission layer on the support. Based upon this recognition and upon testing various solvents and compositions, the following composition of a solution was found to be particularly suitable, namely:

15	Dinitrocellulose (e.g., collodion cotton E1440) —g—	20
	Butoxyl ——————ml—	200
	Butylacetate ——————ml—	400
	Butylglycol ——————ml—	200
	Polyacrylacidester 40% dissolved in xylol ——————ml—	200

A film made with the aid of this solution has a considerably greater strength than a film permeated with filling substances, such, for example, as alkaline earth carbonates.

The compound foil comprising the paste layer with the supporting film therefor, is in particularly advantageous manner placed upon the cathode carrier by bonding the paste layer directly to the cathode carrier, with the supporting film facing to the outside. The cathode carrier can thereby be wetted with the solvent so as to obtain a good bonding effect and therewith good adhesion of the paste layer on the cathode carrier.

The procedure explained above results, as compared with other methods, in very important advantages. A cathode produced in such manner is *a priori* provided with a protective film which prevents damage to the sensitive emission paste layer in the course of assembly operations, which is particularly true when considering the very small grid-cathode spacings customarily provided in present day tube structures. Moreover, as contrasted with previously known methods, the emission paste layer is upon placement thereof on a cathode carrier, in no manner subjected to mechanical stresses. Accordingly, there is no need for increasing the binder component so as to obtain good cohesion. It is indeed possible in using the described method, to reduce the binder content used, for example, in the spraying procedure, to an amount lying below that used in connection with prior methods. As a consequence, the cathodes produced in accordance with the present invention, as contrasted with previously known cathodes, show no tendency of blackening as a result of decomposition of the corresponding carbonate layer in connection with the activation thereof in the discharge vessel.

The blackening of cathodes occurs particularly when the binder, which as such burns completely to form gaseous compounds, namely, oxygen of the carbon, hydrogen and nitrogen, is in the manner of pigments permeated with alkaline earth carbonate (or rather the latter permeated by the binder) causing incomplete decomposition and thereby producing among others, free carbon. The produced free carbon has the property of strongly radiating heat, whereby the cathode temperature may be reduced to a value below the optimum operating value. In addition, the free carbon can react to form carbides with the free barium in the layer, which is responsible for the activity of the cathode, thereby harming the emission. The carbides as such perform high efflux work (poor emission) and can moreover form hydrocarbon substances with water vapor in the residual gas in the tube, such hydrocarbon substances causing in the manner of a cycling process a continuous consumption of the activating barium of the emission layer (continuous poisoning of the cathode).

Further details of the invention will now be described with reference to the accompanying drawing.

FIG. 1 shows at the right hand portion thereof part of a supporting film with an emission paste layer provided thereon, and at the left portion the manner in which such a compound foil is bonded to a cathode, a tubular cathode being indicated to give an example;

FIG. 2 illustrates the manner of producing the supporting film; and

FIG. 3 indicates the manner of producing the emission paste layer.

The strip-shaped so-called compound foil, a portion of which is shown at the right hand part in FIG. 1, comprises the supporting film 3 and the emission paste layer 2. Both, the film and the layer as a unit, are subdivided into sections corresponding in width, for example, in the case of tubular cathodes, to the length of the latter. The left part of the figure shows the manner in which a section of the compound foil is by a rolling operation bonded to a cathode carrier, such, that the emission paste layer 2 is in direct engagement with the metallic carrier 1 while the supporting film 3 faces outwardly. The paste layer is thereby in no way subjected to mechanical stresses but is in fact in the direction of the cathode carrier body continuously even though slightly densified.

It is of course understood that, if needed, for example, in connection with irregularly shaped cathodes, the two layers can be arranged in reversed sequence with respect to the cathode body.

The emission paste layer can be produced either in accordance with prior methods or, in particularly advantageous manner, by spreading and drawing the layer over a support. The supporting film may be produced similarly.

FIG. 2 shows on a greatly enlarged scale the manner of making the supporting film. The lower end of a suitable supply receptacle, which contains an appropriate solution or suspension, forms or is connected with a capillary nozzle 4 having a slot-like opening through which the solution is discharged. The angularly shaped discharge end of this nozzle, with the fluid discharging therefrom, is drawn over a smooth support in a direction extending in parallel therewith, with the edge of its longer side in engagement with the support, the edge of its shorter side thereby defining with respect to the support a very narrow space through which the fluid issues, thus leaving on the support a very thin film 3 of synthetic material in the form of a long strip of desired width. The amount of fluid which is being discharged per time unit is substantially determined by the size of the capillary discharge opening and its spacing from the support. The speed of motion of the nozzle along the support can be varied depending upon the viscosity of the fluid so as to obtain in any case a foil of very exact and particularly uniform thickness. It is of course understood that it is possible to operate with a stationary nozzle and to move the support with respect thereto.

The important individual values must be empirically established in view of the considerable shrinkage occurring during the drying of the supporting film made in the above described manner. A practical value for the width of the nozzle is, for example, 0.3 millimeter which is relatively great compared with the thickness of the film which may amount to 8 up to 10 microns.

After the solvent has sufficiently evaporated, the film can be severed from its support, for example, by immersion in water, and can be dried at approximately room temperature by air blown against it.

However, the operation will generally be such that the film, while being on its support, is provided with the emission paste layer and is, after appropriate drying in air, removed from the support as a unit together with the paste layer, at a temperature of about 100°C.

It is in addition to the above explained properties necessary that the supporting film withstand the drying

temperature for the emission paste layer without undergoing any changes.

As shown in FIG. 3, the emission paste layer may be advantageously produced in a similar manner as the supporting film, utilizing the latter as a support therefor. The emission paste is contained in a suitable container provided with a nozzle 4 having a discharge opening which is narrower than that of the corresponding nozzle for the film fluid, as shown in FIG. 2, such opening being, for example, of a size from 0.1 to 0.13 millimeter. The nozzle is moved with respect to the previously prepared supporting film 3, leaving thereon an emission paste layer 2. The solvent contained in the paste fluid effects slight partial dissolution or softening of the supporting film, thereby providing an increased bonding action and producing the desired compound foil.

Both, the emission layer and the supporting film can be produced as continuous strips with the aid of appropriate automatic machinery, for example, with the aid of a foil drawing machine.

The emission paste layers produced according to the invention have a density of about 1.3, that is, a relatively high density, as compared with layers made, for example, by spraying, in accordance with a prior method. A subsequent densifying, for example, by pressing, as previously proposed, is therefore unnecessary in connection with compound foils or emission layers made as described herein.

The important advantages obtained by emission layers 30 made according to the invention, as compared with emission layers produced with the aid of prior methods, reside primarily in that the compound foils, consisting of a supporting film and an emission paste layer, have greater strength and good flexibility, and that they are, as compared with the known separable paste films, practically not at all mechanically stressed. Since the amount of binder material in the emission paste layer can be held very small, there is no danger of formation of black carbonate layers (residual carbon). The construction of the 35 compound foil provides for the emission paste layer, after the latter is joined with the cathode body, a protective layer (supporting film) which prevents damage thereto that may be caused incident to the assembly operation in view of the small grid-cathode spacing to be realized in present day tubes. The surface of the emission layer (paste layer) made according to the invention, which 40 adjoins the supporting film, is particularly smooth. However, this smooth surface of the emission layer is after decomposition of the supporting film exposed, that is, it will 45 face the grid cooperating with the cathode. Since the supporting film is in a cathode prepared for operation as described herein, disposed on the outside, that is, on the side facing away from the cathode body, there is assurance that it will completely decompose without leaving 50 disturbing residues. The invention is applicable for producing emission layers in connection with the practically all forms of cathodes and likewise in connection with mass production, providing nevertheless very uniform and primarily dense and very smooth layers.

60 The paste for forming the emission layer may be ground and emulsified to provide a particle size which is smaller than about 6 microns.

Changes may be made within the scope and spirit of the appended claims which define what is believed to be new and desired to have protected by Letters Patent.

I claim:

1. A method of forming thin emission layers upon carriers for directly or indirectly heated cathodes of electrical discharge vessels, comprising placing upon the smooth surface of a very thin pliable support film, substantially made of dinitrocellulose of a thickness from 8-10 microns, an emission layer in the form of a paste consisting substantially of an alkaline earth carbonate intermixed with a binder of dinitrocellulose and softener agents, with the binder facilitating adhesion of said paste

to said film to produce a compound foil formed of said film and layer, bonding said compound foil to said cathode member with the emission layer thereof in engagement with such member, and upon operation of the cathode, incident to decomposing action of the emission layer, effecting decomposition of said film without leaving any disturbing residue or liberating aggressive gas.

2. A method according to claim 1 comprising the step of wetting said cathode member with a solvent prior to bonding said foil thereto.

3. A method according to claim 1, wherein said compound foil is formed upon a support from which it is after drying thereof removed at a temperature of about 100° C.

4. A method according to claim 1, wherein said paste is a suspension of alkaline earth carbonate containing a binder of dinitrocellulose in the amount of about 2 to 2.5 percent by weight, said paste being applied directly to said film.

5. A method according to claim 1, comprising grinding and emulsifying said paste so as to make the particle size thereof smaller than 6 microns.

6. A method according to claim 1, wherein said film is made from a composition containing 24 g. dinitrocellulose, 200 ml. butoxyl, 400 ml. butylacetate, 200 ml. butylglycol, and 200 ml. polyacrylacidester dissolved in 5 40% xylol.
